UNITED STATES PATENT OFFICE.

CARL H. BISSELL, OF SYRACUSE, NEW YORK, ASSIGNOR TO GROUSE-HINDS COMPANY,
OF SYRACUSE, NEW YORK, A CORPORATION OF NEW YORK.

HOUSING AND SWITCH-OPERATING MEANS FOR LAMP SOCKETS.

1,408,855.

Specification of Letters Patent.

Patented Mar. 7, 1922.

Application filed May 3, 1919. Serial No. 294,580.

To all whom it may concern:

Be it known that I, CARL H. BISSELL, a citizen of the United States, and a resident of Syracuse, in the county of Onondaga and State of New York, have invented a certain new and useful Housing and Switch-Operating Means for Lamp Sockets, of which the following is a specification.

This invention relates to outlet boxes used for housing electrical appliances as lamp sockets, etc., having switches associated therewith, and has for its object a particularly simple, efficient and durable means associated with the box for readily engaging with the operating elements or keys of said appliances whereby said elements are operable from the outside of the boxes. The invention consists in the combinations and constructions hereinafter set forth and 20 claimed.

In describing this invention, reference is had to the accompanying drawings in which like characters designate corresponding parts in all the views.

25 Figure 1 is a face view of an outlet box or housing embodying my invention, a lamp socket being shown therein.

Figure 2 is a fragmentary vertical sectional view of parts seen in Fig. 1.

30 Figures 3 and 4 are detail perspective views of parts of the operating member carried by the box.

This invention comprises an electrical outlet box, or housing, an electrical appliance 35 mounted in the box and having a switch operating element associated therewith and operating means carried by the box and constructed to readily interlock with said element.

40 1 designates the box which may be of any suitable form, size and construction, it being here shown as being open at one side and formed with means as an internally coarse threaded flange 2 for receiving a globe not shown. The box is also shown as formed with a hooded top and a portion 3 projecting laterally from the top and provided with suitable means as nipples 4 for connection with electrical conduits through which the 45 service wires extend to and from the appliance in the box.

50 5 is the electrical appliance as a lamp socket provided with a laterally extending key 6 for operating the switch of the socket. 55 The socket is placeable in the box through

the open side, and is secured in any suitable manner to the support 7 secured by screws 8 to posts 8^a depending from the top.

The operating member carried by the box is here shown as rotatable and journaled in a 60 lateral side wall of the box arranged at an angle to the open side and is formed with means for interlocking with the key 6.

9 is the operating member here shown as having a shank 10 journaled in a bushing 11 65 threaded in the side wall of the box and in a bushing 12 threading in the former bushing 11. The shank being arranged in axial alignment with the key 6. The operating member 9 is also formed with a socket 13 at 70 the inner end of the shank 10, said socket being open at its inner end and at one side so that it will receive the head of the key 6 as the socket is being mounted in the box. The socket 13 is here shown as U-shaped 75 with the intermediate part of the U mounted on the shank 10. A spacer 14 is located on the shank 10 between the socket 13 and the bushing 11. A suitable handle 15 is mounted on the outer end of the shank and secured thereto as by a screw 16 and by interlocking slots and tongues 17, 18 on the hub 19 of the handle and on the outer end of the shank. The hub 19 of the handle 80 abuts against the bushing 12 so that the spacer 14 and hub hold the operating member 85 from axial movement.

The support 7 for the socket and the posts 9 in the box are so arranged that the key of the socket will come in substantial axial 90 alignment with the operating member 9 on the box.

In operation, when the socket is being placed in the box, the key 6 is turned so that the head thereof stands with its long dimension parallel to the axis of the socket that is vertical in Fig. 2, and the operating member 9 is also turned so that the socket 13 likewise stands vertically. Hence, during movement of the lamp socket into the box 100 the head of the key slides in the socket 13 through one of the open sides thereof and interlocks with the socket 13. After the lamp socket has been secured in position, the key 105 can be operated by turning the handle 15 of the member 9.

This construction of box and switch operating member is particularly advantageous in that standard appliances or sockets can be readily placed in and removed from the box 110

and the switch operating element as keys of said appliances can be readily engaged with and disengaged from the operating member carried by the box.

5. What I claim is:

The combination of a box open at one side, an electrical socket mounted in the box and placeable therein through the open side, the socket having a key extending laterally 10 therefrom toward a lateral side of the box which lateral side is arranged at an angle to the open side, and an operating member

mounted in said lateral side of the box, means for securing the socket in the box with the key in alinement with the operating 15 member, the key and operating member being formed to interlock upon movement of the socket into the box, substantially as and for the purpose described.

In testimony whereof, I have hereunto 20 signed my name at Syracuse, in the county of Onondaga, and State of New York, this 8th day of April, 1919.

CARL H. BISSELL.
